Des. 219,958
Patented Feb. 23, 1971

219,958

DISPENSER FOR TOILET BOWL CLEANING COMPOSITION

Charles W. Clark, 95 Andover Ave.,
Dumont, N.J. 07628

Filed Oct. 20, 1969, Ser. No. 19,612

Term of patent 14 years

Int. Cl. D9—07

U.S. Cl. D9—223

FIG. 1 is a perspective view of a dispenser for toilet bowl cleaning composition embodying my new design;

FIG. 2 is an elevational view, the opposite side being the same in appearance;

FIG. 3 is an elevational view looking from the right of FIG. 2, the opposite side being the same in appearance; and

FIG. 4 is a bottom plan view thereof.

I claim:

The ornamental design for a dispenser for toilet bowl cleaning composition, as shown and described.
